UNITED STATES PATENT OFFICE.

ROBERT PLATO, OF NEW YORK, N. Y.

HAT.

SPECIFICATION forming part of Letters Patent No. 740,913, dated October 6, 1903.

Application filed June 5, 1903. Serial No. 160,187. (No model.)

To all whom it may concern:

Be it known that I, ROBERT PLATO, a citizen of the United States, and a resident of the city of New York, borough of Manhattan, in 5 the county and State of New York, have invented a new and Improved Hat, of which the following is a full, clear, and exact description.

The invention relates to summer or outing 10 hats made of canvas or like fabric material, and its object is to provide a new and improved hat arranged to allow free circulation of air through the crown to keep the wearer's head cool and to greatly strengthen and reinforce 15 the rim to prevent the latter from losing its shape.

The invention consists of novel features and parts and combinations of the same, as will be more fully described hereinafter and then 20 pointed out in the claims.

A practical embodiment of the invention is represented in the accompanying drawings, forming a part of this specification, in which similar characters of reference indicate corresponding parts in both views.

Figure 1 is a perspective view of the improvement, and Fig. 2 is a partial enlarged cross-section of the same.

The crown A of the hat has its upper portion A' formed of a closely-woven fabric, such as cotton-duck or the like, and the lower or base portion A² of the crown is formed of one or two annular bands of an open-mesh fabric, such as flat braids secured to a perforate or 35 wide open-mesh fabric strip, the latter and the braids forming a double perforate band, and the said crown portions A' and A² are lined on the inside by a lining B, of a wide open-mesh fabric, so as to bring the meshes 40 of the crown portion A² in register with the meshes of the lining B for the free circulation of air through the crown.

The perforate base portion A² of the crown is preferably secured directly at its lower end 45 to the lining B, and the latter and the base portion are connected at their lower ends to a binding-tape C and the inner edge of a rim

D, preferably made of three layers of cotton-duck and formed at its outer end into a seam 50 containing a reinforcing or strengthening tape E to give the desired stiffness to the rim and

to hold the same against losing its shape. The binding-tape C extends on the outside of the base portion A² and on the top of the inner end of the crown D, thus giving a fine finish 55 to the hat.

A sweat-band F is secured in the usual manner to the rim D, at the inner end thereof, and the said sweat-band is preferably made in three sections F', F², and F³, of which the 60 top and bottom sections F' and F² are made of leather and connected with each other by the section F³, made of a perforate band, such as a flat braid similar to the flat braid used for the crown base portion A². Now by 65 the arrangement described the perforate section F³ of the sweat-band registers with the open-mesh lining B, opposite the perforate base portion A² of the crown, so that air can directly pass to the wearer's head at that portion engaged by the sweat-band. It is understood that air can readily circulate up 70 through the crown by the air passing between the sweat-band F and the lining B.

From the foregoing it will be seen that the 75 base portion A² of the crown, made in the manner described, obviates the use of the ordinary hat-band, as the open-mesh braids serve as hat-bands, and hence give a fine appearance to the hat.

A hat constructed in the manner described 80 can be cheaply manufactured and allows a free circulation of air through the crown to keep the wearer's head cool, and by having the rim reinforced at the outer edge by the 85 tape E, the said rim is not likely to lose its shape in case the hat gets wet.

Having thus described my invention, I claim as new and desire to secure by Letters 90 Patent—

1. An outing-hat provided with a crown formed of an upper portion, of a closely-woven fabric material, a lower or base portion formed of two annular bands, of an open-mesh fabric, and an open-mesh lining for the interior 95 of the crown, extending over both the upper and the lower portions of the crown, as set forth.

2. An outing-hat provided with a crown formed of an upper portion, of a closely-woven 100 fabric material, and a lower or base portion, consisting of flat braids and a strip of wide-

mesh fabric, on which the braids are secured, the said braids forming the hat-band, as set forth.

3. A hat having a crown consisting of an upper portion of a closely-woven fabric material, a lower or base portion in the form of a perforate band, an open-mesh lining for the interior of the crown, carrying the said band, a rim, and an annular binding-tape between the rim and the said lining, as set forth.

4. An outing-hat comprising a rim, a crown having its upper portion formed of a closely-woven fabric, and the lower or base portion

formed of a perforate or open-mesh band, an open-mesh lining for the interior of the crown, carrying the said perforate band, and a binding-tape connecting the said rim with the said lining at the outside thereof, as set forth.

In testimony whereof I have signed my name to this specification in the presence of two subscribing witnesses.

ROBERT PLATO.
